UNITED STATES PATENT OFFICE.

FRANK HOWARD CRUMP, OF LOS ANGELES, CALIFORNIA.

HOLDER FOR LOOSE-LEAF BINDERS.

1,229,894.

Specification of Letters Patent. Patented June 12, 1917.

Application filed September 1, 1916. Serial No. 118,04

To all whom it may concern:

Be it known that I, FRANK H. CRUMP, a citizen of the United States, and a resident of Los Angeles, in the county of Los Angeles and State of California, have invented a certain new and useful Improvement in Holders for Loose-Leaf Binders, of which the following is a specification.

My present invention relates generally to supports for loose leaf binders while the leaves thereof are being marked, typewritten, or otherwise engrossed, and among various objects of my invention I aim to provide means for temporarily supporting a loose leaf binder with its detachable sheets, so that the binding members may be removed and the sheets freed.

A further object is to provide means for tilting the sheets in such a position that each sheet may be readily fingered separately, when one is to be placed in a typewriter, and in numbers when consecutive sheets are not to be typewritten or otherwise engrossed.

25 A still further object is to provide means for rapidly separating or offsetting those sheets which have been typewritten upon or otherwise engrossed, from those which have not been engrossed.

30 A still further object is to provide means for supporting a detachable leaf binder in such a manner that the binding members can be readily inserted through the sheets and through the binder members and the 35 sheets locked in the binder in their new positions after being separately handled and typewritten on and their relative positions changed in the manner which will be presently described.

40 Further objects of the invention, residing more particularly in the structural details thereof, and the advantages thereof, will be better understood from the following description, reference being made to the accompanying drawings, forming a part of 45 this specification, and in which—

Figure 1 is a perspective view illustrating my invention and its practical application as a loose leaf binder is initially placed 50 thereon;

Fig. 2 is a similar view illustrating a loose leaf binder in initial position upon the holder;

Fig. 3 is a vertical longitudinal section 55 through my improved holder taken substantially on line 3—3 of Fig. 2.

Fig. 4 is a view similar to Fig. 1, illustrating the second position of the binder upon the holder, with the upper binder member removed from the binder; 60

Fig. 5 is a side elevation showing the parts in substantially the position illustrated in Fig. 4;

Fig. 6 is a plan view, and

Fig. 7 is a vertical transverse section taken 65 substantially on line 7—7 of Fig. 5.

Referring now to these figures, my invention contemplates the provision of a holder including a boxlike body generally indicated at 10, having a base 11, side walls 12 and 13, front and rear end walls 14 and 15, and a top wall forming a supporting surface and including forward and rear sloping portions 16 and 17, these portions sloping inwardly and downwardly from the upper ends of the end walls 14 and 15 as clearly seen in Fig. 3.

This top wall supporting surface also includes centrally located portions 18 and 19, abruptly inclined upwardly and toward one another from the lower inner ends of the sloping end portions 16 and 17 just above mentioned, it being noted that these abruptly inclined portions 18 and 19 are substantially at right angles to the sloping portions 16 and 17, respectively, and meet at their upper ends at a point substantially centrally between the end walls 14 and 15 of the body.

The binder as utilized in my invention is 90 preferably of that type in which upper and lower binder members 20 and 21 have means for detachably engaging the opposite ends of pins 22, the latter of which extend not only through the binder members 20 and 21, 95 but also through the plurality of detachable sheets 23 held therebetween.

The binder is initially placed upon the rear sloping portion 17 of the supporting surface of the holder with the engaged edges 100 of the series of sheets 23 against the upwardly inclined portion 19, as seen in Fig. 3. To this end the sloping portion 17 is provided with a hinged cover 24 adjustable vertically upon its hinge 25, and having a pair 105 of depending curved and pivoted rack members 26 projecting downwardly through openings in the sloping portion 17 of the supporting surface, these racks being controlled by springs 27 and being shiftable on 110 their upper pivots into and out of engagement with fixed stop pins 28, the lower ends

of the rack members 26 being connected by a rod 29 projecting laterally beyond the side wall 13 of the holder and through a curved slot 30 in said side wall, and provided with 5 a handle 31 by means of which the rack members 26 may be shifted out of engagement with the stop pins 28 in lowering the cover 24 from the raised position shown, for instance, in Fig. 5.

10 The abruptly inclined portion 18 of the supporting surface, at the lower end of the forward sloping portion 16, is provided with side guide pieces 32 and 33 extending forwardly along the sloping surface 16 and provided with lower edges 34 spaced above the said surface 16 so as to receive thereunder one edge of the upper binder member 20 after the latter is removed and disposed upon the sloping surface 16 in the position 15 shown in Fig. 5, whereby in the transfer of the sheets 23 from the rear portion of the holder to the forward portion thereof, as they are typewritten upon or otherwise engrossed, the said sheets may be properly 20 positioned with respect to the upper binder member 20. To this end the abruptly inclined portion 18 is provided with a vertical guide strip 35 parallel to and adjacent the guide side piece 33 and by means of which, 25 and the recess 36 at the engaged edges of the sheets 23, the several sheets may be positioned upon the upper binding member 20 disposed upon the surface 16 in laterally offset relation, the sheets typewritten upon being disposed against the guide piece 33 and the sheets not typewritten upon being disposed against the guide piece 32, or vice versa, the coöperation of the recesses 36 and the guide strip 35 preventing the sheets so 30 offset from being thereafter laterally displaced.

It will be noted that the abrupt inclinations of the portions 18 and 19 of the supporting surface, form substantially a triangle, the 35 spaces at the sides of which are occupied by upwardly extended portions of the side walls 12 and 13, the side walls 13 having openings 37 into which the binder pins 22 may be inserted and temporarily disposed 40 while the binder is upon the holder and until it is again assembled for removal therefrom.

The forward sloping surface 16 is preferably provided with a hinged cover 39 adapted to be elevated upon its hinge 40 45 and to rest upon the side guides 32 and 33, in which position the binder, when assembled may be supported for the purpose of reference.

In the use of the holder it may be supported upon any suitable framework such as 50 a supporting stand indicated at 41 in Figs. 1 and 4, adjacent to a typewriter or other machine upon which the several sheets 23 or a part thereof are separately disposed for engrossing. With the rear cover 24 elevated

to a position suitable to the particular operator in order that the sheets may be readily reviewed and readily handled either separately or in series, the sheets are transferred upon the binder member 20 positioned as 55 shown in Fig. 5 upon the forward surface 16, until all of the sheets have been transferred, the pins 22 are then inserted through the sheets 23 and the binder member 20 and locked, the binder member 20 with the sheets thereon is then pulled upwardly along the surface 16 in which a transverse groove 42 is provided into which the lower edge of the binder member 20 may be disposed while the binder member 21 is being disposed and 60 connected to complete the binder before the latter is entirely removed from the holder.

If it is so desired, the openings for the posts are placed in the rear sloping portion 17, and when the lock is released the posts 85 22 may drop automatically into the lower portion of the box with the heads extending out sufficiently to pull them out when the sheets are removed to the front tray.

It is obvious that my invention provides 90 for the complete fulfilment of the foregoing objects, and for material advantages to the operator in handling loose leaf binders as described.

It is further obvious that my invention as 95 shown and described is susceptible of various slight modifications and changes without departing from the spirit thereof, and as permitted under the terms of the following claims:

I claim:

1. A holder of the character described, having its upper supporting surface formed with forward and rear portions sloping inwardly and downwardly from its opposite 105 ends and having centrally located portions abruptly inclined upwardly and toward one another from the lower inner ends of the sloping end portions, each of said sloping end portions having a cover hingedly connected thereto and upwardly movable.

2. A holder of the character described having its upper supporting surface formed with forward and rear portions sloping inwardly and downwardly from its opposite 115 ends and having centrally located portions abruptly inclined upwardly and toward one another from the lower inner ends of the sloping end portions, each of said sloping end portions having a cover hingedly connected thereto and upwardly movable, and means for supporting one of said covers in selected adjustment.

3. A holder of the character described, having its upper supporting surface formed 125 with forward and rear portions sloping inwardly and downwardly from its opposite ends and having centrally located portions abruptly inclined upwardly and toward one another from the lower inner ends of the 130

sloping end portions, one of said abruptly inclined portions having side guide pieces projecting therefrom along the adjacent sloping surface.

5. A holder of the character described, having its upper supporting surface formed with forward and rear portions sloping inwardly and downwardly from its opposite ends and having centrally located portions abruptly inclined upwardly and toward one another from the lower inner ends of the sloping end portions, one of said abruptly inclined portions having side guide pieces projecting therefrom along the adjacent sloping surface, the lower edges of said guide pieces being spaced above the said adjacent sloping surface.

10. A holder of the character described, having its upper supporting surface formed with forward and rear portions sloping inwardly and downwardly from its opposite ends and having centrally located portions abruptly inclined upwardly and toward one another from the lower inner ends of the sloping end portions, one of said abruptly inclined portions having side guide pieces projecting therefrom along the adjacent sloping surface, and a guide strip parallel and adjacent to one of said guide pieces.

15. A holder of the character described having an upper supporting surface including inclined portions substantially at right angles to one another, a hinged cover on one of said inclined portions having a pivoted depending spring controlled rack member, a fixed stop into and out of engagement with which the said rack is shiftable on its pivot, and a handle connected to the rack.

20. The combination with sheets having a plurality of holes adjacent their binding edges uniformly spaced with each other and a single notch open at their binding edges, of binder members including covers and binding posts and means within the binder members for clamping the binder posts, said posts being removably associated with said binder members, and of a binder holder adapted to support said binder members including covers and said sheets when said binding posts have been removed, said binder holder being provided with an offset block which engages the notch in the sheets when in a laterally offset relation, and which engages one side of the sheets when in an alined body, said sheets having a plurality of holes registering whether in an alined body or in a laterally offset relation.

25. The combination with sheets having a plurality of holes adjacent their binding edges uniformly spaced with each other and a single notch open at their binding edge, of binder members including covers and binding posts and means for locking said

binding posts into said binder members, said posts being removably associated with said binder members, and of a binder holder adapted to support said members including covers and said sheets when said binding posts have been removed, said binder holder being provided with an offset block which engages the notch in the sheets when in a laterally offset relation, and which engages one side of the sheets when in an alined body, said sheets having a plurality of holes registering whether in an alined body or in a laterally offset relation, said binder holder being provided with means for supporting one end of one of the binder covers together with the sheets at an acute angle to offset the upper edges of the sheets.

30. The combination with sheets having a plurality of holes adjacent their binding edges uniformly spaced with each other and a single notch at their binding edges, of binder members including covers and binding posts and means for locking said binding posts into said binder members, said posts being removably associated with said binder members, and of a binder holder adapted to support said binder members including covers and said sheets when said binding posts have been removed, said binder holder being provided with an offset block which engages the notch in the sheets when in a laterally offset relation and which engages one side of the sheets when in an alined body, said sheets having a plurality of holes registering whether in an alined body or in a laterally offset relation, said binder holder being provided with means for supporting one end of one of the binder covers together with the sheets at an acute angle to offset the upper edges of the sheets, said binder holder being provided with adjustable side sheet guides to the left and to the right side of the offset block, preventing lateral movement of sheets thrown to said side guides.

35. The combination with sheets having a plurality of holes adjacent their binding edges uniformly spaced with each other and a single notch open at their binding edges, of binder members including covers and binding posts and means for locking said binding posts into said binder members, said posts being removably associated with said binder members, and of a binder holder adapted to support said binder members including covers and said sheets when said binding posts have been removed, said binder holder being provided with an offset block which engages the notch in the sheets when in a laterally offset relation, and which engages one side of the sheets when in an alined body, said sheets having a plurality of holes registering whether in an alined body or in a laterally offset relation, said binder holder being provided with means for supporting one end of one of the

- binder covers together with the sheets at an acute angle to offset the upper edges of the sheets, said binder holder being provided with adjustable side sheet guides to the left and to the right side of the offset block, preventing lateral movement of sheets thrown to said side guides, said binder holder being provided with a groove to receive the lower edge of one of the binder members when said binder and covers are pulled clear of the side guides.
11. The combination with sheets having a plurality of holes adjacent their binding edges uniformly spaced with each other and 15 a single notch open at their binding edges, of binder members including covers and binding posts and means for locking said binding posts into said binder members, said posts being removably associated with 20 said binder members, and of a binder holder adapted to support said binder members, including covers and said sheets when said binding posts have been removed, said binder holder being provided with an off- 25 set block which engages the notch in the sheets when in a laterally offset relation, and which engages one side of the sheets when in an alined body, said sheets having a plurality of holes registering whether in an 30 alined body or in a laterally offset relation, said binder holder being provided with means for supporting the end of one of the binder covers together with the sheets at an acute angle to offset the upper edges 35 of the sheets, means for holding said cover and sheets in a plurality of angles, said binder holder being provided with adjustable side sheet guides to the left and to the right side of the offset block, preventing lateral movement of sheets thrown to said side guides.
12. The combination with sheets having a plurality of holes adjacent their binding edges uniformly spaced with each other and 45 a single notch open at their binding edges, of binder members including covers and binding posts and means for locking said binding posts into said binder members, and of a binder holder adapted to support said 50 binder members, including covers and said sheets when said binding posts have been removed, said binder holder being provided with an offset block which engages the notch in the sheets when in a laterally offset relation, and which engages one side of the sheets when in an alined body, said sheets having a plurality of holes registering
- whether in an alined body or in a laterally offset relation, said binder holder being provided with means for supporting one 60 end of one of the binder covers together with the sheets at an acute angle to offset the upper edges of the sheets, means for holding said cover and sheets in a plurality of angles, and means for quickly bringing 65 said cover and sheets back to normal position, said binder holder being provided with adjustable side sheet guides to the left and to the right side of the offset block, preventing lateral movement of sheets thrown to 70 said side guides.
13. In a binder holder, the combination with sheets having a plurality of holes adjacent their binding edges uniformly spaced with each other, and a single notch open at 75 their binding edges, of binder members including covers, binding posts to normally hold said sheets, means for locking the binding posts in said binder members, and means for holding said binder members and sheets 80 in a position in which the holes in the binder members register with the holes in the sheets whether the sheets are in an alined body or in laterally offset relation, said posts being removably associated with said binder members, said binder holder being provided with an offset block which engages the notches in the sheets when in laterally offset relation, and which engages one side of the sheets when in an alined body. 85
14. In a binder holder, the combination with sheets having a plurality of holes adjacent their binding edges uniformly spaced with each other and a single notch open at 90 their binding edges, of binder members having holes therein and including covers, and binding posts and means for locking said binding posts into the holes of said binder members, means for holding the binder members and sheets in a position in which the holes in the binder members register with a plurality of holes in the sheets whether the sheets are in an alined body or in a laterally offset relation, said binder holder being provided with an offset block which engages the notch in the sheets when in a laterally offset relation, and which engages one side of the sheets when in an alined body, and said binder holder having openings to receive the said binding posts when the latter are released from the said binder members. 95

FRANK HOWARD CRUMP.
